UNITED STATES PATENT OFFICE

140,878

DESIGN FOR A TOY RATTLE

Richard C. Lewis, Winnetka, Ill.

Application June 23, 1944, Serial No. 114,164

Term of patent 14 years

(Cl. D34—15)

To all whom it may concern:

Be it known that I, Richard C. Lewis, a citizen of the United States of America, residing at 1386 Asbury Avenue, Winnetka, Illinois, have invented a new, original, and ornamental Design for a Toy Rattle, of which the following is a specification, reference being had to the accompanying drawing, forming a part thereof.

Referring to the drawing, Fig. 1 is an elevational view of a toy rattle embodying my new design; Fig. 2 is a top plan view and Fig. 3 is a perspective view of the same.

The characterizing features of my design for a toy rattle reside in a plurality of pendants of contrasting colors, suspended from cords attached to a circular top member, said top member being mounted on a flexible member extending downwardly to a square base, said pendants being spaced from said top member and from said base, all as shown.

I claim:

The ornamental design for a toy rattle, substantially as shown and described.

RICHARD C. LEWIS.
